UNITED STATES PATENT OFFICE.

CHARLES DE MINICO, OF BOSTON, MASSACHUSETTS, ASSIGNOR TO UNITED SHOE MACHINERY CORPORATION, OF PATERSON, NEW JERSEY, A CORPORATION OF NEW JERSEY.

METHOD OF AND MACHINE FOR OPERATING UPON SHOES.

Application filed September 20, 1919, Serial No. 325,237. Renewed January 11, 1924.

To all whom it may concern:

Be it known that I, CHARLES DE MINICO, a citizen of the United States, residing at Boston, in the county of Suffolk and State of Massachusetts, have invented certain Improvements in Methods of and Machines for Operating upon Shoes, of which the following description, in connection with the accompanying drawings, is a specification, like reference characters on the drawings indicating like parts in the several figures.

This invention relates to shoemaking and specifically to working portions of a shoe-upper into lasted position, and to evening the bottom surface formed by portions of the upper.

In the manufacture of various kinds of shoes the upper is first pulled over the edge of the insole and the pulled-over portion is then attached temporarily to the insole and subsequently this and other portions are worked inwardly over the insole to tighten the upper against the last. Incidentally to this operation the worked-over portion is plaited or crimped in some places, especially at the ends of the insole, and the crimps or plait must be flattened or reduced in order to even the bottom surface of the shoe before the outsole is laid. If the upper material is thick the aforesaid crimps are very prominent and consequently the difficulty of evening the bottom of the shoe is more difficult and requires more time than when the upper material is thin. These crimps are especially bulky in arctics and other rubber shoes and for this reason it has been the practice heretofore to trim the crimps and then to reduce them further by pounding them. The formation of crimps occurs also in shoes that have uppers made of leather or woven fabric, but for well-known reasons it is sometimes not feasible to trim the crimps in such shoes and it has been the practice to reduce them as much as possible merely by pounding them. In most shoes, when the margin of the upper is first pulled over upon

the insole it is temporarily secured to the latter by a relatively small number of tacks, and in many shoes it is the practice to secure the pulled-over margin to the insole by adhesion with or without the use of tacks.

One object of the present invention is to provide an improved method of making shoes with special reference to the overworking of the upper, the evening of the bottom and the conforming of the upper and the insole to the concavity in the shank portion of the last. In order to disclose as fully as possible the several aspects of the invention it is illustrated and described with special reference to a shoe of the arctic-type since such shoe affords a convenient example for the purpose of disclosure. In one aspect the invention provides an improved method of making shoes which consists in moving the marginal portion of a shoe-upper relatively to the insole in a direction such as to tighten the upper against the last while applying successive pounding impulses to the said portion in a direction to promote adhesion of the marginal portion to the insole as the upper is being tightened.

In a further aspect the invention provides an improved method of making shoes which consists in imparting upper-tightening movement to the marginal portion of the upper by moving the shoe in the plane of a beating face while the latter is vibrating to even the bottom of the marginal portion and to promote adhesion between said portion and the face of the insole. Thus, when the margin of the upper is cemented to the insole with or without additional holding means such as tacks, the pounding or beating element may be utilized not only to even the bottom of the shoe, but to promote adhesion and to tighten the upper against the last by moving the marginal portion inwardly over the insole to its final position on the latter. This combined upper-tightening, bottom-evening and adhesion-promoting operation may be performed progressively around the margin

of the shoe bottom so as to affect all parts of the shoe and if, as is usually the case when a preliminary pulling-over operation has been performed, the pulled-over portion is secured 5 to the insole only at a relatively few points, the combined operation as characterized above may be practiced to work inwardly those portions of the pulled-over marginal portion that lie between the initial points of 10 anchorage, so that the upper may be tightened uniformly at all points and so that all parts of the pulled-over margin may be secured in their final lasted position upon the insole by adhesion.

15 It has been found in practice that these combined operations may be accomplished most successfully by utilizing a pounding instrumentality having a nurled or otherwise roughened work-engaging surface. Such 20 surface has several advantages over a smooth working surface, for example, the small teeth that constitute the working surface indent the marginal portion of the upper sufficiently to obtain a non-slipping grip on the 25 work so that the latter has no opportunity to escape from the working instrumentality while the upper-tightening operation is in progress. Again, in working on rubber-shoes and arctics, in which the marginal 30 portion of the upper is composed largely of rubber, the nurled or otherwise roughened surface of the working instrumentality disintegrates the material and forms a new surface of fresh rubber that is thus exposed, 35 and when an outsole is subsequently applied and secured by cement the latter will adhere more strongly than it would adhere to an old surface. Subsequently to the laying of a rubber-outsole the shoe is subjected to a 40 vulcanizing operation to weld or unite all the elements. The union thus formed by vulcanization is made more effective in consequence of the aforesaid disintegration of the marginal portion of the upper, since 45 new rubber is brought into intimate relation with the outsole preparatory to the vulcanizing operation. Furthermore, the disintegrating effect assists materially in evening the bottom of the lasted shoe, and particularly at the ends, since, at the latter, the 50 margin of the upper is plaited or crimped as hereinbefore mentioned. Incidentally to tightening the upper where the crimps are formed the stock is redistributed and the redistribution is amplified very materially in 55 consequence of the disintegrating effect produced by the pounding instrumentality. The evening effect thus produced is so great that the preliminary trimming of the crimps 60 may be dispensed with entirely.

In another aspect the invention provides a method of working the uppers of boots and shoes into finally lasted position, for instance at the sides of the shoe, which consists in presenting a shoe with its upper in

engagement with a lasting tool at a distance from the bottom edge of the upper and turning or rocking the shoe to transfer the area of effective engagement of the tool with the upper toward the bottom edge of the upper 70 and to work the margin of the upper inwardly and press it into adhering relation to the bottom face of the insole.

75 In still another aspect the invention provides for conforming the shank portion of a shoe, particularly a rubber-shoe or arctic, to the shank portion of the last. To this end it is preferable to use a pounding instrumentality of convex form and having a degree of 80 convexity that enables it to enter the deepest part of the hollow in the shank portion of the last. For this purpose a roll is a simple and efficient form of pounding instrumentality, and such roll may have a diameter 85 of about two inches, with its periphery constituting the working surface. The machine shown by the accompanying drawings is provided with a pounding roll the periphery of which is nurled or otherwise roughened to grip and to disintegrate the marginal portion of the upper as aforesaid. The tool thus formed is adapted to depress the insole and the marginal portion of the upper into the deepest part of the shank of the last and to execute the combined pounding, disintegrating and upper-tightening operations at 90 this part of the shoe simultaneously with the operation of conforming the shoe to the hollow of the last.

95 The pounding roll is preferably mounted upon a central pin or stud so as to be capable of turning about its axis in addition to imparting the aforesaid pounding impulses in lines transverse to its axis. The final stages 100 of evening the bottom of the lasted shoe may, therefore, be conveniently performed by moving the shoe in directions that cause the nurled roll to turn about its axis while the pounding operation is in progress. In 105 order to assist the operative in this respect it is desirable to use a guide-roll in such relation to the pounding roll as to roll on the side of the shoe while the bottom of the shoe is held against the pounding roll, both rolls being preferably arranged to turn in response 110 to movements of the shoe that cause the pounding roll to pound progressively along the margin of the shoe bottom.

115 Referring to the accompanying drawing in which a machine adapted to carry out the method of the invention is illustrated,—

120 Fig. 1 represents an elevation, partly in vertical section, of a pounding machine with which a portion of a partially lasted shoe is shown in one working position;

125 Fig. 2 is a view including the pounding instrumentality and the guide roll against both of which a portion of the shoe is held in another position;

130 Fig. 3 represents an end view of the

pounding roll occupying the concaved shank portion of the shoe, the heel portion of which is at the left;

Fig. 4 represents a bottom view of a shoe 5 the upper of which has been pulled over and partially lasted and its margin secured to the insole by adhesion and tacks; and

Fig. 5 represents a sectional view on a relatively large scale showing a fragment of 10 a shoe containing a last and a fragment of a toothed pounding tool acting on the pulled-over margin of the upper, the margin being indented by the teeth of the tool.

The machine may embody any suitable 15 design but for the purposes of illustration and not of limitation the machine selected embodies a general organization similar to that of the pounding mechanism disclosed in United States Letters Patent No. 1,019,878, 20 granted Mar. 12, 1912 on application of Orrell Ashton.

The pounding instrumentality indicated at 10 is carried by a movable holder that includes two parts indicated at 12 and 14 respectively. For the purpose of affording adjustment the part 12 is provided with a dovetailed rib 16 and the part 14 is provided with a correspondingly formed portion adapted to clamp said rib. In order to afford such clamping action the part 14 is split throughout a portion of its length and the portions so separated from each other are provided with a clamping screw 18 arranged to draw them together against the rib 16. 25 The holder 12, 14 is arranged to slide bodily in suitable guides afforded by fixed elements 20, 22, according to the structure and arrangement of the corresponding elements shown in said patent. The part 14 includes 30 a portion 24 arranged to be acted upon by an operating cam 26. This cam is carried by a shaft 28, and the latter may be driven by any suitable means, preferably at a speed that will produce rapid vibration of the 35 pounding instrumentality. A body of fibrous material 30 such as felt is arranged to be engaged by the cam 26 and is intended to be saturated with a lubricant to minimize friction between the cam and the portion 24 of the vibratory holder. The fixed element 22 supports an adjustable plate 32 in position to contact with a portion of the part 14 to limit the movement of the vibratory holder toward the cam. This plate is 40 adjustable relatively to the element 22 and may be clamped at any desired position by a clamping bolt 34. The guides in which the vibratory holder moves are inclined so that the latter will normally gravitate toward the position to be occupied by the work, and the range of movement of the holder is such that when the latter is in its extreme 45 forward position the portion 24 will be out of the range of action of the cam, and the pounding instrumentality will, therefore,

remain stationary in its forward position excepting when it is moved into the range of action of the cam.

In the present instance the working instrumentality is a cylindric roll, this form being preferred for some kinds of work, but the invention, in its broad aspect, is not limited to this form of pounding instrumentality. Furthermore, the pounding roll, as shown in Fig. 1, is divided transversely of 70 its axis into a plurality of sections each of which is a complete roll in itself. These sections are mounted upon a stud 36 that is carried by the part 12 of the vibratory holder, and the roll sections are free to rotate relatively to each other and are capable of endwise movement relatively to the holder. An important feature of the pounding instrumentality is that its working surface is composed of closely related teeth 38 80 (Fig. 5), and these teeth are preferably sharply pointed. In order to produce teeth suitable for operating as explained herein, the periphery of the roll may be nurled while the metal is comparatively soft, and the roll would preferably be hardened after being so formed. I have found that teeth of pyramidal form are desirable and effective for the purposes of this invention. 85

A guide roll 40 is supported in position to roll upon the side of a shoe while the bottom of the shoe is in working relation to the pounding instrumentality. The guide roll in the present instance is loosely mounted upon a stud 42 and this stud is affixed to 90 an adjustable bracket 44. The bracket 44 is affixed, in turn, to another adjustable bracket, the latter being indicated at 46. The bracket 46 is affixed to frame-part 48 of the machine by means of a clamping bolt 50. 100 Bracket 44 is connected to bracket 46 by a clamping bolt 52. Bracket 46 is adjustable in vertical lines relatively to the frame-part 48, and bracket 44 is adjustable in horizontal lines relatively to bracket 46. 110

Stud 42 is provided with a head 54 for confining the guide roll, but the latter is free to move endwise and also to rotate relatively to the stud, the range of endwise movement being limited by the head 54 and bracket 44. The axis of stud 42 is preferably inclined so that the roll will normally gravitate toward the operative and away from the axis of stud 36. 115

In the use of the machine the manipulation of the shoe will depend to some extent on the character of the work, although the general principles will be the same with all kinds of work. Fig. 4 represents a bottom view of a partially lasted rubber shoe in 120 which the marginal portion 56 of the upper has been pulled over upon the margin of the insole 58, and secured to the latter by cement and by lasting tacks 60. Heretofore, in lasting rubber shoes, it has been neces- 125

sary to perform a complete lasting operation by hand or by a lasting machine before subjecting the lasted shoe to a pounding operation. Ordinarily it has been necessary 5 to drive a relatively large number of lasting tacks to hold the pulled-over margin of the upper in the desired lasted position and to maintain tension throughout the upper. By virtue of this invention, however, 10 the preliminary lasting operation may be materially curtailed as by driving only a relatively few lasting tacks, if any, prior to performing the pounding operation; the tool acting as a lasting tool to work the 15 upper tightly over the innersole. In any case, where the upper is worked over the ends of the last, the worked-over portions have to be puckered or crimped, as indicated at 62, and these crimped or wrinkled portions have to be pounded down or otherwise 20 reduced before the shoe is in condition to receive the outsole. When the margin of the upper is cemented to the insole, with or without additional holding means such as 25 lasting tacks, the pounding and overdrawing action as effected in accordance with the present invention produces several distinct results.

For example, when the margin of the upper is pressed against the pounding instrumentality with sufficient force to move the portion 24 of the vibratory holder into the range of action of the operating cam the latter strikes a series of sharp and rapid 30 blows that cause the teeth 38 to indent the marginal portion as shown by Fig. 5. So long as the work is held against the pounding instrumentality with sufficient pressure to maintain the indented or interlocked relation, as shown by Fig. 5, this relation may 35 be utilized to draw the marginal portion inwardly over the bottom of the insole to complete the lasting operation, to promote adhesion between the marginal portion and the insole, and to reduce the crimps or lumps in the said portion. Furthermore, 40 the teeth disintegrate the overlaid marginal portion and effect a redistribution of material so that the excess of material at some 45 points is transferred to those points where there is no excess. The overdrawing action may be performed conjointly by the vibratory action of the pounding instrumentality in lines indicated by arrows *a* 50 and by movement of the shoe in the direction indicated by arrow *b*. When the shoe is so moved the marginal portion of the upper that is interlocked with the teeth 38 remains in substantially fixed relation 55 to the pounding instrumentality so that at this point of the work the said portion is caused to creep inwardly relatively to the insole. It is to be understood that this operation should be performed at a time when 60 the cement or other adhesive substance be-

tween the overlaid marginal portion and the insole is in a condition that will maintain the said portion in the position to which the latter is moved, as described.

In some cases the work may be presented 70 to the rolls in the position shown by Fig. 2, wherein the overlaid portion of the upper is held against the pounding roll while the side of the shoe rests upon the guide roll. The latter is preferably rounded as indicated at 64 to provide a smooth bearing for 75 the work and to avoid marking the latter. According to Fig. 2 the guide roll is against its supporting bracket 44, having been moved to that position by the movement of 80 the work toward the pounding roll. If the work be turned as indicated by arrows *c* in Fig. 2, while maintaining pressure of the work against the pounding roll, the overdrawing action of the latter upon the upper will occur first at or beyond the edge of 85 the insole, but as the turning of the work progresses the area of contact between the pounding roll and the marginal portion of the upper will advance toward the opposite edge of the shoe, and the roll will ultimately bear upon the bottom of the shoe, as shown by Fig. 1. Incidentally to this manipulation of the shoe the guide roll will 90 move endwise from the position shown by Fig. 2 to that shown by Fig. 1, the guide roll thus constituting a movable support for the shoe without forming any appreciable resistance to the manipulation of the 95 shoe.

In rubber shoe work the insole is usually thicker in the middle part than around the margin, the relatively thick part constituting a filling that will be substantially level with the overlaid margin of the upper when the latter has been pounded down to final position. The overdrawing action as executed by the pounding instrumentality 100 serves to draw the edge of the upper to the edge of the filling portion of the insole and when the work is in the position shown by Fig. 1, the teeth of the pounding roll act simultaneously upon the marginal portion of the upper and upon the filling portion 105 of the insole, and these two elements of the work are thus leveled relatively to each other and the bottom of the shoe is left in 110 the desired condition for the reception of an outsole.

The final leveling or evening of the shoe 115 bottom may be conveniently effected by moving the shoe back and forth horizontally from side to side while the shoe is resting against both rolls, as shown by Fig. 1. If, in the course of such manipulation, 120 the shoe is moved otherwise than strictly at right angles to the axis of either roll one or both rolls will move endwise as occasion may require to avoid forming an appreciable 125 resistance to such manipulation.

- In working the shank portion of the shoe into the acutely concaved shank portion of the last indicated by dotted lines at 66 in Fig. 3, the shoe will be held so that the contour of the last will correspond to the periphery of the pounding roll. In order to obtain the most desirable conformation to this portion of the last the pounding instrumentality, whether it be in the form of a roll or not, would preferably have a curvature of small enough radius to enable it to go into the deepest part of the shank. Thus, the pounding instrumentality may be utilized not only to complete the lasting of the shoe throughout the shank portion, as by overdriving the marginal portion of the upper, but it may be used to conform both the insole and the over-worked and lasted portion of the upper to the hollow of the shank of the last.
- Having thus described my invention, what I claim as new and desire to secure by Letters Patent of the United States is:
1. The method of operating upon a shoe the marginal portion of the upper of which is held by adhesion to the insole, which consists in moving said portion of the upper relatively to the insole in a direction to tighten the upper against the last, and applying successive pounding impulses to said portion in a direction to promote adhesion as the upper is being tightened as aforesaid.
  2. The method of operating upon a shoe the marginal portion of the upper of which is held by adhesion to the insole, which consists in executing a series of percussional impacts against said portion in a direction to promote adhesion of the latter to the insole while maintaining stress on said portion continuously throughout the period including said impacts and in a direction such as to move the latter inwardly over the insole.
  3. The method of operating upon a shoe the marginal portion of the upper of which is held by adhesion to the insole, which consists in continuously pulling the margin of the upper inwardly over the insole while causing a series of pressing impulses of the pulling means and said margin, one against the other, in a direction to promote adhesion of the upper to the insole.
  4. That step in a method of making shoes which consists in imparting upper-tightening movement to the margin of the upper overlying the insole by moving the shoe transversely of its length in the plane of a beating face while maintaining contact with the beating face.
  5. That step in a method of making shoes which consists in imparting upper-tightening movement to the margin of the upper overlying the insole by moving the shoe axially of a transversely movable beating roll while holding the margin in contact with the periphery of the roll.
  6. The method of operating upon a shoe the marginal portion of which is held to the bottom of the insole by adhesion, which consists in executing upper-tightening movements of said portion and pressure impulses in a direction to promote adhesion of the marginal portion to the insole.
  7. The method of operating upon a shoe of which the margin of the upper is worked over a last and held by adhesion to the insole, which consists in simultaneously pounding and indenting the said margin of the upper and moving the shoe relatively to the pounding-and-indenting instrumentality in a direction such as to force the margin of the upper further inwardly over the insole from the edge of the latter while the pounding-and-indenting operation is in progress.
  8. The method of operating upon a partially lasted shoe the marginal portion of which is crimped and cemented to the insole at one end of the shoe, which consists in simultaneously pounding and indenting the crimped portion and moving the shoe relatively to the pounding-and-indenting instrumentality in a direction such as to force the crimped portion inwardly over the insole from the edge of the latter and to final lasted position while the pounding-and-indenting operation is in progress.
  9. The method of operating upon a partially lasted shoe the marginal portion of which is cemented to the insole, which consists in simultaneously pounding and indenting the marginal portion progressively around the periphery of the shoe-bottom, and completing the lasting by moving the shoe repeatedly, during the pounding-and-indenting operation and relatively to the pounding-and-indenting instrumentality, in directions such as to work the marginal portion inwardly into final lasted position upon the insole.
  10. That improvement in methods of lasting shoes, which consists in cementing one or both of the confronting surfaces of the insole and upper, fastening the margin of the upper temporarily in pulled-over relation to the insole, pounding the pulled-over portion of the upper in lines such as to promote adhesion of the upper and insole, moving the shoe relatively to the pounding instrumentality in a direction such as to work the pulled-over portion inwardly from the edge of the insole, and advancing the shoe step-by-step relatively to the pounding instrumentality to repeat the pounding and the working-in action progressively along the edge of the shoe.
  11. The method of operating upon a partially lasted shoe of which one or both lapped faces of the upper and insole are adhesive, which consists in pounding the marginal portion of the upper against the insole and simultaneously moving the shoe

- relatively to the pounding instrumentality about an axis extending lengthwise of the shoe so as to work said portion inwardly from the edge of the insole.
12. The method of operating upon a partially lasted shoe of which one or both lapped faces of the upper and insole are adhesive, which consists in causing the overlaid margin of the upper to creep inwardly from the edge of the sole by pounding the margin and simultaneously moving the work relatively to the pounding instrumentality in lines substantially parallel to the bottom of the last and transversely thereof to draw the margin inwardly from the edge of the insole. 70
13. The step in a method of making a shoe of which the margin of the upper is overlaid on an insole, which consists in simultaneously pounding said margin and disintegrating the surface thereof. 75
14. The step in a method of making a shoe of which the margin of the upper comprises rubber and is crimped upon the margin of the insole, which consists in simultaneously disintegrating and pounding the crimped portions. 80
15. The step in a method of making a shoe of which the margin of the upper comprises rubber and is lapped over upon the margin of the insole, which consists in simultaneously pounding, disintegrating, and redistributing the substance of the margin of the upper. 85
16. The step in a method of making a shoe of which the margin of the upper comprises rubber and is cemented to the margin of the insole in lapped relation, which consists in simultaneously pounding and disintegrating the margin of the upper and simultaneously moving the shoe relatively to the pounding instrumentality to work the margin inwardly from the edge of the insole. 90
17. The method of operating upon a partially lasted shoe the marginal portion of which is cemented to the insole, which consists in pressing said portion against a positively operated pounding tool having work-indenting spurs on its pounding surface, and moving the shoe to tighten the upper against the last while the indenting pressure of the work and tool is maintained. 100
18. The method of lasting a shoe of which one or both of the confronting faces of the upper and the insole are adhesive, which consists in pulling over the marginal portion of the upper and securing the latter to the insole at a comparatively few points, and thereafter simultaneously pounding and shifting the portions between said points progressively and relatively to the insole to work the said portions inwardly between said points. 110
19. The method of operating upon the crimped portions at one end of a lasted shoe of which said portions are composed of rubber, which consists in simultaneously disintegrating, pounding, and redistributing said crimped portions to equalize the distribution of substance and to form a new surface. 115
20. The method of operating upon a partially lasted rubber shoe the marginal portion of the upper of which is held to the insole by adhesion at the shank-portion, which consists in pounding the marginal portion and the insole into the deepest part of the hollow in the shank of the last, and moving the shoe relatively to the pounding instrumentality, while maintaining pressure of the shoe against said instrumentality, in a direction such as to draw the said portion inwardly to final lasted position upon the insole at said deepest part. 120
21. A machine for operating upon shoes comprising the combination with means for imparting rapid percussional impulses, of a serrated beating roll operatively connected to said means and arranged at an altitude and angle convenient for an operative to hold a shoe with its bottom pressed against the periphery of the roll with a component of pressure directed axially of the roll. 125
22. A machine for operating on a partially lasted shoe, comprising a pounding tool for acting on the marginal portion of the upper, and means for imparting positive hammering action to the tool to pound said portion, said tool having a dentate work-engaging surface to prevent relative edge-wise movement of the upper so as to draw the upper inwardly and tension it over the edge of the insole into final lasted position upon transverse movement of the shoe relatively to the lines of pounding movement. 130
23. A machine for operating on a partially lasted shoe, comprising a pounding roll the periphery of which is arranged to act on the margin of the upper, a reciproitable holder for said roll relatively to which the roll is free to turn, and means for imparting positive hammering action to said holder to pound said margin, said periphery embodying a dentate formation to prevent outward movement of the margin transversely of its edge and to draw the margin inwardly from the edge of the insole in consequence of moving the shoe relatively to the roll and axially thereof. 135
24. A machine for operating on a partially lasted shoe, comprising a pounding tool having a working surface formed by a group of pointed spurs for acting on the overlaid portion of the upper, and means for imparting positive hammering action to said tool to impress said spurs into said portion so as to grip the latter positively by the cooperation of the insole, said tool being thereby effective to overdraw and to tension the upper positively in consequence of relative movement of the shoe and the tool. 140

25. A machine for operating on a partially lasted shoe, comprising a pounding roll having a peripheral working surface formed by closely related pointed spurs for acting on the overlaid portion of the upper, and means for imparting positive hammering action to said roll to impress some of said spurs into the work so that the latter will be gripped positively by the roll with the co-operation of the insole, said roll being free to turn relatively to said means and being effective to draw the work inwardly from the edge of the insole in consequence of relative movement of the shoe and the tool.
- 15 26. A machine for operating on a lasted shoe, comprising a pounding roll having a peripheral working surface for acting on the overlaid portion of the upper, said surface being formed by closely related pointed spurs adapted to disintegrate the surface of the overlaid portion, and means for imparting positive vibratory hammering action to said roll transversely of its axis, said roll being free to roll and to move endwise relatively to said means in response to movement of the shoe during the pounding operation.
- 25 27. A machine for operating on a lasted shoe, comprising a pounding roll for acting on the bottom of the shoe, a guiding roll for traversing the side of the shoe, and means for imparting positive vibratory hammering action to said pounding roll to pound the work, said rolls being movable endwise in response to oblique feeding movement of the shoe.
- 35 28. A machine for pounding shoes, comprising a pounding roll, a holder therefor, a work-guiding roll, one of said rolls being movable endwise in response to oblique feeding movement of the shoe, and means for vibrating said holder to pound the work.
- 45 29. A machine for pounding shoes, comprising a pounding roll, a holder therefor, a work-guiding roll the axis of which is substantially at right angles to that of the pounding roll, each of said rolls being movable endwise in response to oblique feeding movement of the shoe, and means for vibrating the holder to pound the work.
- 55 30. A machine for pounding shoes, comprising a pounding roll, a holder therefor, a work-guiding roll the axis of which is inclined to cause it to gravitate normally away from the pounding roll, each of said rolls having limited freedom to move endwise, and means for vibrating said holder to pound the work.
- 60 31. A machine for pounding shoes, comprising a pounding roll, means for vibrating the roll to pound the work, and a work-guiding roll supported in co-operative relation to the pounding roll to form an angle for the reception of a portion of the shoe, each of said rolls being free to turn and free to move endwise relatively to the other, one of said rolls being arranged to gravitate normally toward the axis of the other and the latter being arranged to gravitate normally away from the axis of the one specified.
- 65 32. A machine for pounding shoes, comprising a pounding tool, means for operating said tool to pound the work, and a roll having a surface convexly curved longitudinally of its axis for guiding the work at varying angles with relation to the pounding tool.
- 75 33. That improvement in methods of lasting shoes which consists in presenting a shoe with its upper in engagement with a lasting tool at a distance from the bottom edge of the upper and turning or rocking the shoe to transfer the area of effective engagement of the tool with the upper toward the bottom edge of the upper and to work the margin of the upper inwardly and press it into adhering relation to the bottom face of the insole.
- 80 34. That improvement in methods of lasting shoes which consists in engaging the upper at a distance from its bottom edge with a driven lasting tool adapted to act by friction to tighten the upper over the last, and while holding the shoe in frictional engagement with the lasting tool turning or rocking the shoe to transfer the area of its engagement with the tool toward the bottom edge of the upper and to work the margin of the upper inwardly and press it into adhering relation to the bottom face of the insole.
- 85 35. That improvement in methods of lasting shoes which consists in engaging the upper at a distance from its bottom edge with a driven lasting tool adapted to act by friction to tighten the upper over the last, and while holding the shoe in frictional engagement with the lasting tool turning or rocking the shoe to transfer the area of its engagement with the tool toward the bottom edge of the upper and to work the margin of the upper inwardly and press it into adhering relation to the bottom face of the insole.
- 90 36. That improvement in methods of lasting shoes which consists in engaging the upper at a distance from its bottom edge with a driven lasting tool adapted to act by friction to tighten the upper over the last, and while holding the shoe in frictional engagement with the lasting tool turning or rocking the shoe to transfer the area of its engagement with the tool toward the bottom edge of the upper and to work the margin of the upper inwardly and press it into adhering relation to the bottom face of the insole.
- 95 37. That improvement in methods of lasting shoes which consists in presenting a shoe with its upper in engagement with a frictional lasting tool and in such position that the bottom face of the insole is inclined to the shoe engaging face of the tool, and turning or rocking the shoe in engagement with the tool to bring the bottom face of the insole into substantially parallel relation to the shoe engaging face of the tool to tighten the upper over the last and to press its margin into adhering relation to the insole.
- 100 38. That improvement in methods of lasting shoes which consists in presenting a shoe with its upper in engagement with a frictional lasting tool and in such position that the bottom face of the insole is inclined to the shoe engaging face of the tool, and turning or rocking the shoe in engagement with the tool to bring the bottom face of the insole into substantially parallel relation to the shoe engaging face of the tool to tighten the upper over the last and to press its margin into adhering relation to the insole.
- 105 39. That improvement in methods of lasting shoes which consists in presenting a shoe with its upper in engagement with a frictional lasting tool and in such position that the bottom face of the insole is inclined to the shoe engaging face of the tool, and turning or rocking the shoe in engagement with the tool to bring the bottom face of the insole into substantially parallel relation to the shoe engaging face of the tool to tighten the upper over the last and to press its margin into adhering relation to the insole.
- 110 40. That improvement in methods of lasting shoes which consists in presenting a shoe with its upper in engagement with a frictional lasting tool and in such position that the bottom face of the insole is inclined to the shoe engaging face of the tool, and turning or rocking the shoe in engagement with the tool to bring the bottom face of the insole into substantially parallel relation to the shoe engaging face of the tool to tighten the upper over the last and to press its margin into adhering relation to the insole.
- 115 41. That improvement in methods of lasting shoes which consists in presenting a shoe with its upper in engagement with a frictional lasting tool and in such position that the bottom face of the insole is inclined to the shoe engaging face of the tool, and turning or rocking the shoe in engagement with the tool to bring the bottom face of the insole into substantially parallel relation to the shoe engaging face of the tool to tighten the upper over the last and to press its margin into adhering relation to the insole.
- 120 42. That improvement in methods of lasting shoes which consists in presenting a shoe with its upper in engagement with a frictional lasting tool and in such position that the bottom face of the insole is inclined to the shoe engaging face of the tool, and turning or rocking the shoe in engagement with the tool to bring the bottom face of the insole into substantially parallel relation to the shoe engaging face of the tool to tighten the upper over the last and to press its margin into adhering relation to the insole.
- 125 43. That improvement in methods of lasting shoes which consists in presenting a shoe with its upper in engagement with a frictional lasting tool and in such position that the bottom face of the insole is inclined to the shoe engaging face of the tool, and turning or rocking the shoe in engagement with the tool to bring the bottom face of the insole into substantially parallel relation to the shoe engaging face of the tool to tighten the upper over the last and to press its margin into adhering relation to the insole.
- 130 44. That improvement in methods of lasting shoes in which the margin of the upper is fastened to the insole by adhesion, which

consists in presenting the side of the shoe in engagement with a frictional lasting tool and while maintaining the shoe in continuous engagement with said tool turning 5 or rocking the shoe laterally until the bottom face of the insole is substantially parallel to the shoe engaging face of the tool to tighten the upper over the last and to press

its margin into adhering relation to the insole and imparting pounding impulses to the tool to effect adhesion between the upper and insole.

In testimony whereof I have signed my name to this specification.

CHARLES DE MINICO.
